UNITED STATES PATENT OFFICE

163,613

LAMP

Vito A. La Mura, Worcester, Mass.

Application January 9, 1950, Serial No. 7,087

Term of patent 14 years

(Cl. D48—20)

To all whom it may concern:

Be it known that I, Vito A. La Mura, a citizen of the United States, residing at Worcester, in the county of Worcester and State of Massachusetts, have invented a new, original, and ornamental Design for Lamp, of which the following is a specification, reference being had to the accompanying drawing, forming part thereof.

Fig. 1 is a perspective view of a lamp showing my new design; and

Fig. 2 is a view in side elevation thereof on a reduced scale.

I claim:

The ornamental design for a lamp, as shown.

VITO A. LA MURA.
